CLAIM

The ornamental design for a storage container, as shown and
described.

DESCRIPTION

FIG. 1 is a perspective view of a storage container showing
our new design;

FIG. 2 is a bottom perspective view of the storage container
illustrated in FIG. 1;

FIG. 3 is a rear view of the storage container illustrated in
FIG. 1;

FIG. 4 is a front view of the storage container illustrated in
FIG. 1;

FIG. 5 is a left side view of the storage container illustrated
in FIG. 1;

FIG. 6 is a right side view of the storage container illustrated
in FIG. 1;

FIG. 7 is a top view of the storage container illustrated in
FIG. 1; and,

FIG. 8 is a bottom view of the storage container illustrated
in FIG. 1.

The broken lines show portions of the design that form no
part of the claimed design.

1 Claim, 7 Drawing Sheets
